UNITED STATES PATENT OFFICE.

LOUIS WHITZEL DAMAN, OF PONT ROUGE, CANADA.

FURNACE.

Application filed December 13, 1924. Serial No. 755,698.

The invention relates to a furnace as described in the present specification and illustrated in the accompanying drawings that form part of the same.

The invention consists essentially of the novel features of construction pointed out broadly and specifically in the claims for novelty following a description containing an explanation in detail of an acceptable form of the invention.

The objects of the invention are to conserve the heat generated by directing the flow of the heating gases in a natural course, so that the heat is absorbed in passage into the metal having a maximum heating surface and a free outlet afforded for the waste and cooler gases; to reduce the cost of production and facilitate the operations of the foundry; to enjoy all the advantages of the sectional type of furnace both in the manufacture and the installation; to eliminate the carbonization in the heat radiating elements; to increase the life of the furnace and insure comforts to those heating their houses and buildings by hot air; and generally to provide efficiency at a minimum consumption of fuel in a durable and serviceable furnace.

In the drawings, Figure 1 is a perspective view of the furnace showing one side wall removed.

Figure 2 is a perspective view showing from the front the interior construction.

Figure 3 is a perspective view, showing from the rear the interior construction.

Figure 4 is a vertical sectional view through one of the heat elements, fire pot and base.

Like numerals of reference indicate corresponding parts in the various figures.

Referring to the drawings, the radiator sections 5 are formed of inverted vertical V-shaped flues, each in two pieces secured together by bolts 8 one side 9 being longer than the other side 10 and communicating through the passage 11 between the walls 12 and upper walls.

The firepot 13 in size is made to meet the requirements in regards to the number of sections 5 to be used and is formed of a bowl 14 closed in by the top 15 set thereon and secured by the flange 16. The firepot 13 communicates through the radiator sections 5 with a longitudinal flue 19 formed of the upper and lower sections 18 and 17,

the former having communicating openings to the vertical flues 10 and secured thereto and the latter forming part with the top 15 and the vertical flues 10 fit over the openings 20. The sections 5 are spaced by the bars 21 60 engaging the central pins 22, while the furnace front 23 abuts the front section and the back 24 the rear section, thereby firmly holding the sections in position.

The back wall 24 and side walls 25 and 26 are formed in vertical sections and fit together with overlapping flanges and one of said vertical sections has the water pan 27 extending from the outside through the wall to the inside.

The said vertical sections are formed of outer and inner walls 28 and 29 spaced to form cold air passages and having outlets 30 at the lower end thereof through the inner walls 29; the said passages registering 70 with passages in the furnace cap 31 that connects with the customary cold air channels.

The firepot bowl 14 is mounted on the base 32, which is formed with lugs 33 for the walls and an outer retaining flange 34 completely therearound and carrying a support 35 thereon for the rear end of the firepot. In the operation of the furnace the usual fuel for this type is wood and the heating is by warm air descending from the furnace enclosure through the passage provided in the cap and through the usual channels to the rooms to be heated.

The heating gases from the firepot enter the long legs of the heat sections and rise 80 to the body portion where they hang until the heat is absorbed by the metal wall of the body and radiated therefrom into the enclosure rising quickly through the cap. There is no descent of the heating gases, so 85 long as they remain hot as the tendency to rise is inherent in the lighter heated air, consequently the flow down the short legs 10 will always be the waste portion of the gases quite cool and of no service for heat and 90 this flow will enter the flue and be dissipated in atmosphere through the usual piping and chimneys.

What I claim is:

1. In a furnace, a plurality of vertical flues in inverted U-shape having inlets at the lower end on the one side and outlets at the other side, a firepot and a closure mounted thereon having inlets to said flue inlets and carrying a flue extending there- 100 110

along and communicating with said outlets and a casing enclosing said parts and affording a hot air furnace.

2. In a furnace, a plurality of vertical flues in inverted U-shape having inlets at the lower end on the one side and outlets at the other side, a firepot and a closure mounted thereon having inlets to said flue inlets and carrying a flue extending there-

10 along and communicating with said outlets and a casing enclosing said parts and affording a hot air furnace and having a firebox opening in the front thereof.

3. In a furnace, a plurality of vertical flues in inverted U-shape having inlets at the lower end on the one side and outlets at the other side, each of said inverted vertical flues formed of two flanged pieces bolted together, a firepot and a closure 20 mounted thereon having inlets to said flue inlets and carrying a flue extending therealong and communicating with said outlets and a casing enclosing said parts and affording a hot air furnace.

25 4. In a furnace, a plurality of vertical flues in inverted U-shape having inlets at the lower end on the one side and outlets at the other side, each of said inverted vertical flues formed of two pieces secured together 30 and elliptical in cross section at their lower ends and open at the bottom, a firepot and a closure mounted thereon having inlets to said flue inlets and carrying a flue extending therealong and communicating with said 35 outlets and a casing enclosing said parts and affording a hot air furnace.

5. In a furnace, a plurality of vertical

flues in inverted U-shape having inlets at the lower end on the one side and outlets at the other side and having rounded top distanced by spacing bars, a firepot and a closure mounted thereon, having inlets to said flue inlets and carrying a flue extending therealong and communicating with said outlets and a casing enclosing said parts and 45 affording a hot air furnace.

6. In a furnace, a plurality of vertical flues in inverted U-shape having inlets at the lower end on the one side and outlets at the other side, a firepot and a closure 50 mounted thereon having inlet to said flue inlets and carrying a longitudinal chimney flue communicating with said vertical flue outlets and a casing formed of vertical sections having cold air passages therewithin 55 enclosing said parts and affording a hot air furnace.

7. In a furnace, a plurality of vertical flues in inverted U-shape having inlets at one lower end on the one side and outlets at 60 the other side, a firepot and a closure mounted thereon having inlets to said flue inlets and carrying a flue extending therealong and communicating with said outlets and a casing formed of vertical sections 65 having outer and inner walls spaced to form cold air passages and having outlets at the lower end thereof through said inner walls, said casing enclosing said parts and affording a hot air furnace. 70

Signed at Pont Rouge this 30th day of August 1924.

LOUIS WHITZEL DAMAN.
